UNITED STATES PATENT OFFICE.

EDWIN LANE, OF NEW YORK, N. Y., ASSIGNEE TO CAROLYN LAUNDRY, OF NEW YORK, N. Y., A CORPORATION OF NEW YORK.

LAUNDRY CHECKING DEVICE.

Application filed April 24, 1925. Serial No. 25,593.

My invention relates to checking devices especially adapted for use in laundries for identifying garments and other pieces, and to enable the pieces belonging to each customer to be re-collected. The invention is not limited in utility, but may be employed wherever conditions are suitable. Brief explanation hereafter of its use in laundry systems is sufficient to enable its adaptability 10 to other uses to be understood.

The general object is to provide a marker of exceedingly simple form, and which may therefore be produced at low cost, which has improved means for quick and easy attachment to a fabric, without injury to the fabric, and which also admits of easy detachment, together with a "check" designed to cooperate with a similarly configurated "key" in assorting the finished "wash", this 20 check being suitably connected to the marker.

A more particular object is to avoid disadvantages or defects of previous checks which are provided with fabric-attachment devices in the form, substantially, of safety pins. These pins are loosely connected to the checks, which therefore hang free from the fabric and cause inter-tangling of checks, interference with laundry apparatus, and other difficulties well known to laundrymen. 30 Such difficulties I overcome by making the marker and check devices and the attachment devices, in preferred forms of the invention, actually or substantially integral, or at least rigidly connected.

Another particular object is to provide a suitable check device, to cooperate with the usual key, in combination with a known form of marker, consisting of flexibly-connected opposed jaws provided with fabric grips, and adapted for operation by a special tool, or a machine, in applying the marker to and removing it from laundry pieces.

The characteristics and advantages of the invention are further sufficiently explained in the following detail description of certain structures chosen as representative examples. Skilled persons will understand that many variations may be made, and I contemplate the employment of any structures that are properly within the scope of the appended claims.

In the drawings—

Fig. 1 is a perspective view of a combined marker and checker, embodying the invention in one form, applied to a fabric;

Fig. 2 is a perspective view of a plurality of markers in place on a key;

Fig. 3 is a section at 3—3, Fig. 1;

Fig. 4 is a perspective view of a modified marker-check;

Fig. 5 is a similar view of another modification.

The combined check and marker in the forms illustrated in Figs. 1 to 3 is preferably made of a single piece of resilient sheet metal, such as brass or copper. It includes substantially flat, opposed jaws 1 and 2, connected by a curved spring-portion 3, and provided with cooperating fabric-gripping lugs 4 and sockets or apertures 5. These formations are produced by punching or pressing operations. The lugs 4 have blunt tops, which force fabric without injury into the apertures or sockets, and grip it so tightly as to prevent accidental displacement. The jaws are also formed with other apertures 6, each terminating at one end in a socket 7. The apertures 6 permit the insertion into the sockets of the nibs of a special spreading tool, which is manipulated like a pair of pliers to spread the jaws while a fabric is placed between them; the jaws are then permitted to converge and grip the fabric, and the tool is withdrawn. Of course if desired the check or tag may be applied by any suitable machine. After laundering the marker is removed by substantially reverse operations.

In suitable places, such as a face of one or both jaws 1, 2, an identifying number or legend 8 is placed, by stamping or otherwise.

One of the jaws, such as 2, has an integral lateral check extension 10, large enough for the formation therein of an opening 11, to receive a key 12, Fig. 2, which shows a number of the markers strung on the key. The identifying numbers 8 of all these markers are the same, and the key is provided with distinctively arranged ribs 13 or otherwise formed to cooperate with a corresponding configuration of the check-apertures 11, this configuration consisting in this example of slots 14 corresponding to the key-ribs. This rib and slot, or other analogous mode of key and check-aperture configuration, provides for almost unlimited permutations, a different cooperation formation being provided for each key and its set of identically numbered markers, so that the sorter need depend on numbers only as a guide to the 118

particular sorting compartment at which the appropriate key is located, and then when placing the fabric in the compartment the check-opening 11 of the marker is passed over the key, and the fitting of the key shows that the identification of the garment or fabric is correct, and failure to fit shows that an error has been made, which is then corrected by re-inspection of the identification number.

The marker may be located on a fabric as shown in Fig. 1, or preferably may be placed in fuller engagement with the fabric so that the marker and its integral check are substantially entirely located within the limits of the fabric, and there is no projecting part of consequence to catch in laundry machinery or cause trouble in other ways. Similar annoyances from loosely connected checks, as where safety-pin attachments are used (referred to above) are also avoided. The check-portion lies smooth and flat in line with one of the jaws against one face of the fabric. The device is probably of maximum simplicity and low cost for a combined marker and check arranged for ready attachment and removal in the manner described.

Fig. 4 shows a modification in which the combined check and marker consists of a single flat piece of sheet metal, 20, which may be rectangular as shown, or of other suitable shape. The check opening 11 is formed centrally in the marker, and has key-corresponding slots 14 and an identifying number 8, as in the previous example. The marker also has a plurality of small thread-holes 21, located near the corners, or elsewhere, so that suitable means such as a sewing machine or hand needle may be used to secure the marker to a garment or fabric by a thread or threads passed through the holes 21. The marker is easily removed by breaking the thread.

In the variation shown in Fig. 5 prongs

30 are provided, which may be stamped and bent up from the body of the marker, and which are stuck through a fabric and clinched to hold the marker in place. This attachment means may be employed for many classes of laundry pieces which are not appreciably injured by perforation or thread-displacement caused by the prongs.

I claim:

1. A marker-check for purposes described, comprising a substantially flat body of moderate thickness having integral rigid means for attachment to a laundry-piece and also having formed therein a check-perforation configurated to match a certain key.

2. A marker-check for laundry comprising a body provided with integral means for attachment to a laundry piece, said body being provided with an integral lateral extension at one side having a perforation therein bounded entirely by rigid immovable walls integral with the body and one or more of said walls being provided with a ward configured to match a certain key.

3. A marker-check for laundry comprising an intermediately bent strip of flat spring metal having flat members with a clear space between them and provided with normally closed jaws continuing therefrom, one of said jaws being formed with integral inwardly extending projections, the other jaw being provided with apertures into which the projections force portions of the laundry piece, and one of said jaws being provided with an integral lateral extension at one side having a perforation therein bounded entirely by rigid immovable walls integral with the jaw, and having one or more walls provided with a ward configured to match a certain key.

Signed at New York, in the county of New York and State of New York.

EDWIN LANE.
